AUTOMATIC STAPLING MACHINE

Romeo M. Nardone, Teaneck, N.J.

Application November 8, 1949, Serial No. 126,111

8 Claims. (Cl. 1-3)

1

This invention relates to power machinery, and particularly to the control of a motor-driven machine for applying and securing wire segments to a plurality of sheets or layers of paper, cloth, or other materials to be clasped together.

An object of the invention is to provide, in a motor-driven stapling machine, novel means for controlling the application of operating power to the reciprocable stapler head.

A second object of the invention is to provide, in a motor-driven stapling machine, novel means for timing the duration of each successive period of power application, to produce perfect synchronization between the starting and stopping of power application, on the one hand, and the successively attained positions of the stapler head, on the other.

A third object of the invention is to provide, in a motor-driven stapling machine, novel electrical connections operating to interrupt the motor drive on each withdrawal stroke of the stapler head, while maintaining the motor in continuous rotation.

A fourth object is to provide, in a motor-driven stapling machine, a novel electro-mechanical interlock operating to prevent re-establishment of the motor drive to the stapler head, following each stapling stroke, until the material being stapled has been (a) withdrawn, and (b) shifted to a new staple-receiving position, or replaced by new material to be stapled.

A fifth object is to provide, in a power-driven stapling machine, novel adjustable means for causing the stapling stroke to begin automatically in response to insertion of the material into the machine to a depth corresponding to the pre-selected marginal spacing at which receipt of the staple is desired.

A sixth object is to provide novel mechanical motion translating connections between a rotating shaft and a reciprocating stapler head; such connections including a torsionally wound spring serving, first, as a resilient thrust transmitter, and secondly, as an automatic shock absorber on each returned stroke of the staple head.

These and other objects of the invention will be understood upon examination of the following description of the form of invention illustrated in the accompanying drawings wherein:

Figure 1 is a front sectional view of a machine embodying the invention;

Figure 2 is a side sectional view;

Figure 3 is a view in perspective of certain of the operating elements, showing their relationship to certain other parts, and to each other;

2

Figures 4, 5, and 6 are diagrams showing three successive positions of the drive controlling switch arm, and the corresponding positions of the solenoid-operated inter-locking element; Fig. 7 is an exterior view, on a reduced scale; and Figure 8 is a diagram of the electrical parts and connections.

Fig. 9 is a side elevation view of the machine. Referring to the drawings, a geared motor 1 having a right angle drive shaft 2 is mounted on base 3. Base 3 also carries the anvil-frame of the stapler unit 4, located thereon by a strap, and locked at the front end by a retainer 6. A multiple toothed clutch element 7 is keyed and pinned to the motor shaft 2. Housing 8 is designed to be mounted concentric with the drive shaft 2 on the outlet flange of the geared motor. This housing supports the driven shaft 9 on ball bearing 10 and plain bearing 11, the former definitely locating the shaft in the housing. Movable clutch element 12 is splined to the driven shaft and is moved by a yoke 13 supported on shaft 52 in housing bore 53. Shaft 52 is drilled for the reception of a de-clutching return spring 14 acting between stationary housing 15 and shaft 52. The opposite end of the yoke is pinned to the end of plunger 16 of a solenoid 17 which latter is fixed to the lower part of bracket 26. Shaft 9 also carries cam member 18 which is screwed to the shaft in a manner to tighten the cam during operation. Associated with cam 18 is a cam follower in the form of a ball bearing 19 carried by operating arm 20 pivoted at 21 on the stapler proper and serving to transmit a downwardly directed pressure upon the stapler head by way of leaf springs 22. The purpose of the springs is to form a resilient pressure transmitting agency between the cam follower 19 and the stapler head, also to take care of any tolerance variations and to yield slightly at the end of the stroke, thus absorbing shock.

As the cam 18 turns upwardly, from its low point in each revolution, thereby relieving the downward pressure on the stapler head, the usual built-in springs, not shown, become effective to press the stapler head upwardly, away from the anvil-frame; the said springs being pre-set to exert pressure upwardly at all times, as is the conventional practice in stapling machines.

A second solenoid 23 is located in the casing parallel with the stapler and the outer end of its plunger 24 is pivotally connected to the inner end of a switch opening arm 25 extending through a slot in a supporting bracket 26 and terminating in an upwardly extending head. The bracket 26

acts as a support for a normally closed micro-switch 27 having an arm 28 also extending through a slot in the bracket 26. A lateral extension strip 29 is riveted to the extended portion of the arm 28 and normally lies behind the head of the arm 25 when the switch 27 is closed as of the arm 25 when the switch 27 is closed as clearly shown in Fig. 2. This prevents the solenoid plunger 24 pulling the switch opening arm to the left when the solenoid 23 is energized as clearly shown in this figure. The switch opening arm 25 is power operated to open the micro-switch 27 and in the form illustrated the switch opening arm 25 has a slot 30 which is engaged by a pin 31 on the movable head of the stapler 4 so reciprocable movement of the stapler head rocks the opening arm 25 on its pivotal connection with the plunger 24 of the solenoid 23. When the stapler head is moved down by the cam 18, through the pin 31, the parallel arm 25 is carried along with it but the micro-switch is not opened. If the solenoid 23 is energized a rearward or pull to the left is exerted upon the opening arm 25 but the upward head of said arm engaging behind the lateral arm extension 29 of the micro-switch 27 prevents retraction of the 25 arm 25 until the upward head of the arm 25 is moved beneath the plane of the part 29. Then the plunger 24 of the solenoid 23 is retracted to withdraw the arm 25 to a position where its head is beneath the extension 29 of the micro-switch 27 operating means. The micro-switch opening power is applied when the stapler head moved up after the stapling is complete and the cam 18 has passed its low point. The pin 31 will lift the arm 25 and the head being under the extension 29 of the switch arm 28 will open the micro-switch 27 as best shown in Fig. 6. Upon de-energization of the solenoid 23, a spring 33 mounted at the pivot between its plunger 24 and opening arm 25 moves said parts forwardly or toward the right until the upward head of said arm clears its operating position beneath the extension of the switch arm 29 whereupon the micro-switch 27 returns to normally closed position. Meanwhile the opening arm 25 is being moved upwardly by the return movement of the head of the stapler 4 so the head of the arm returns to its normal holding original position shown in Figs. 1 and 2.

Operation of solenoids 23 and 17 is brought about through a main micro-switch 34 fixed in the position, upon base 3, to which it has initially been adjusted; the switch being shiftable along a screw 37 to provide such initial adjustment. Its arm is moved by the work to be stapled. Insertion of the work closes the switch to energize both solenoids; the current flowing as indicated in Fig. 8. The solenoid 17 is first de-energized as described and pulling the work away de-energizes solenoid 23. The operation of this portion of the system is as follows:

Switch 34 is closed by the work to be stapled, thereby sending current direct to solenoid 23 and, through switch 27, to solenoid 17. The plunger of solenoid 23 is prevented from moving until the stapler head has made part of its stroke downwardly below extension 29. Toward the end of the stapler stroke, the arm 25 is freed from extension 29, and moves the head of the arm 25 in under extension 29, where it is in a position to open the contacts of switch 27 when the stapler head goes up. At this time, solenoid 17 is de-energized and the motor drive is disconnected. When the work is retracted, switch 34 is opened and solenoid 23 is de-energized. Its plunger

spring 33 then moves arm 25 to its original outward location with its head in front of switch extension 29, permitting the same to drop back to close switch 27. Further upward movement of the stapler head moves the arm 25 to interlocking position, to prevent immediate re-operation of plunger 24 when switch 34 is closed. If this were not so, such re-operation would open the circuit to solenoid 17 before the stapler could make its power stroke.

Switch 34 determines at what point the work is to be stapled in relation to the leading edge of that work. Moving the switch away causes stapling to be made further back from the leading edge of the work. Thumb screw 37 serves to permit bracket 36 (to which switch 34 is bolted) to be moved backward or forward in relation to the stapler head.

A cast aluminum cover hinged at two places 52 to the base encloses the entire mechanism. This cover has a curved slot 53 running along the entire front serving to guide the work into the stapler and to cause contact with the operating arm of switch 34. Injury to the operator is thus avoided.

A main toggle switch to start and stop the motor is located at the front of the mounting base, at 54. The main leads are brought in through a hole (not shown) at the back of the base.

The complete operation is as follows:

Closing toggle switch 54 starts the motor and brings current to switch 34. The part to be stapled is inserted through the cover slot in line with an arrow on the cover (see Fig. 7) designating the location of the stapler head. (The latter may also be seen through the slot.) The work contacts switch arm 35, and closes the switch contacts to energize solenoids 23 and 17. The latter acts immediately to move clutch element 12 into mesh with motor clutch element 7 to drive cam 18. This in turn moves the stapler head down against the part to be stapled, carrying with it the pin 31 and arm 25, the latter clearing the switch extension 29 and thus freeing the solenoid plunger 24 so that it moves extension 25 under the strip 29. (See Fig. 5.) After the stapler completes its down stroke and moves up under the action of its own built-in springs, arm 25 also moves up to open the circuit of switch 27. (See Fig. 6.) Current to solenoid 17 is cut off by such opening of switch 27, and spring 14 disengages the clutch elements 7 and 12. Solenoid 23 remains energized until the stapled matter is drawn away, at which time the switch 34 is opened cutting off the current to that solenoid. Plunger spring 33 then urges arm 25 forward out from under switch arm 29, closing that switch (as in Fig. 4). The cycle may now be repeated.

The words "stapler," "stapling mechanism," and "stapling machine" are used herein in the broad sense, that is, to include any unit serving to apply fastening wire, pins, rivets, or other clasping means, to a plurality of sheets or layers of material to be united or even the reciprocable head of a marking machine; and the structures illustrated are merely suggestive of any and all mechanical equivalents capable of being substituted into any complete organization directed to the practice of the invention disclosed.

What I claim is:

1. In a stapling machine or the like of the reciprocable head type, an electric motor and a circuit, a main control switch for said circuit closed by insertion of the work in the machine

and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression but opened by return movement of the head to break the circuit to the electro-magnetically operated clutching means and permit spring return of the clutch to disconnect the head depressing means and motor, switch opening means movable with the head, means normally holding said switch opening means against movement to switch opening engagement during depression of the head, and means to move said switch opening means into a position to release the holding means therefor and to permit it to open said switch after the downward movement of the head is completed.

2. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression but opened by return movement of the head to break the circuit to the electro-magnetically operated clutching means and permit spring return of the clutch to disconnect the head depressing means and motor, switch opening means movable with the head, means normally holding said switch opening means against movement to switch opening engagement during depression of the head, a second electro-magnetic means in said circuit to move the switch opening means to a switch opening engaging position at approximately the limit of head depression where the switch opening means is released and the switch may be opened by return movement of the head, said second electro-magnetic means being de-energized upon opening of the main control switch by withdrawal of the work, and additional means to move the switch opening means out of switch opening engagement and return the same to normal holding position during completion of the return movement of the head.

3. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression but opened by return movement of the head to break the circuit to the electro-magnetically operated clutching means and permit spring return of the clutch to disconnect the head depressing means and motor, a pivoted switch opening arm movable with the head, an extension on said normally closed switch movable to open the switch against its biased closed position, a head on said switch opening arm normally in a plane above said extension and held thereby against movement past the exten-

sion, means to urge the head toward said extension and to move the same to a position beneath the extension when the opening arm is carried down by the depression of the stapler head to a point where the arm head is below the extension whereby the switch is opened when the stapler head returns, and additional means to reverse the movement of the switch opening arm to move the head of the same from beneath the switch extension to permit closing of said switch and resumption of the previously held position.

4. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression but opened by return movement of the head to break the circuit to the electro-magnetically operated clutch means and permit spring return of the clutch to disconnect the head depressing means and motor, a pivoted switch opening arm movable with the head, an extension on said normally closed switch movable to open the switch against its biased closed position, a head on said switch opening arm normally in a plane above said extension and held thereby against movement past the extension, means to move the said arm and head to a position beneath the plane of the extension as the switch opening arm is carried down by the depression of the stapler head to a point where the arm head is below the extension, a second electro-magnetic means in the circuit to move the said head beneath the switch extension to permit closing of the switch upon return movement of the stapler head, and said second electro-magnetic means being energized and de-energized by the main control switch that is operated by insertion and withdrawal of the work.

5. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression but opened by return movement of the head to break the circuit to the electro-magnetically operated clutching means and permit spring return of the clutch to disconnect the head depressing means and motor, a pivoted switch opening arm movable with the head, an extension on said normally closed switch movable to open the switch against its biased closed position, a head on said switch opening arm normally in a plane above said extension and held thereby against movement past the extension, means to move the said arm and head to a position beneath the plane of the extension as the opening arm is carried down by the depression of the stapler head to a point where the arm head is below the extension, a second electro-magnetic means in the circuit to move the said head beneath the switch extension to permit closing of the switch upon return movement of

the stapler head, said second electro-magnetic means being energized and de-energized by the main control switch that is operated by insertion and withdrawal of the work, and additional means to return the switch opening arm and head to their original position upon de-energization of said second electro-magnetic means.

6. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head depressing means to the motor to depress the head, a normally closed switch in said circuit unaffected during head depression, power means to open said switch during return movement of the head to break the circuit to the electro-magnetically operated clutching means and permit spring return of the clutch to disconnect the head depressing means and motor, switch opening means associated therewith, means normally holding said switch opening means against movement to switch opening engagement during depression of the head, and means to move said switch opening means into a position to release the holding means therefor and to permit it to open said switch after the downward movement of the head is completed.

7. In a stapling machine or the like of the reciprocable head type, an electric motor and a circuit, a main control switch for said circuit closed by insertion of the work in the machine and opened when the work is removed, head depressing means, a clutch between the head depressing means and motor that is spring biased to open position, electro-magnetic means energized by the closed circuit to clutch the head de-

pressing means to the motor to depress the head, a normally closed switch in said circuit unaffected during head depression, power means to open said switch during return movement of the head to break the circuit to the electro-magnetically operated clutching means and permit spring return of the clutch to disconnect the head depressing means and motor, switch opening means associated therewith, means normally holding said switch opening means against movement to switch opening engagement during depression of the head, a second electro-magnetic means in said circuit to move the switch opening means to a switch opening engaging position at approximately the limit of head depression where the switch opening means is released and the switch may be opened during return movement of the head, said second electro-magnetic means being de-energized upon opening of the main control switch by withdrawal of the work, and additional means to move the switch opening means out of switch opening engagement and return the same to normal holding position during completion of the return movement of the head.

8. A machine as defined by claim 1 wherein the head depressing means comprises a cam, and a shock absorber interposed between the cam and machine head.
